UNITED STATES PATENT OFFICE

2,451,379

COMPRESSOR PUMP

Byron R. Burke, Los Angeles, Calif.

Application May 26, 1945, Serial No. 595,985

7 Claims. (Cl. 103—173)

1

This invention relates to improvements in compressors or pumps and may be regarded as an improvement over the construction disclosed in my prior Patent No. 2,106,236, issued January 25, 1938.

In my prior patent there is disclosed a compressor wherein there is a central wobble plate surrounded by an annularly arranged group of cylinders within which pistons are reciprocable. The pistons are normally urged to the bottoms of their strokes within the cylinders by compression springs but are forced to the tops of their strokes by connectors which operatively connect the pistons with the wobble plate. When the wobble plate is driven at relatively low speeds this type of construction has proven quite satisfactory. However, when the wobble plate is driven at high speeds the inertia of the pistons is such that the springs are incapable of maintaining the pistons in tight or firm engagement with the connectors. Consequently under these high speed conditions the connectors and pistons momentarily separate from each other, the separation being almost instantly taken up by the springs urging the pistons to the bottoms of their strokes. This momentary separation of the pistons from the connectors which is immediately taken up results in considerable noise and objectionable vibration as well as being conducive to unnecessary wear.

An object of the present invention is to provide an improved compressor or pump having a wobble plate around which cylinders are arranged and within which cylinders, pistons are reciprocable that are urged to the bottoms of their strokes by compression springs and to provide a novel connection between the wobble plate and the pistons which will enable the wobble plate to be driven at high speeds without having the attendant objectionable vibration or noise.

More specifically, an object of the invention is to provide a connection construction between the pistons and the wobble plate which will permit the connectors to drop or fall away from their pistons under high speed conditions and which will effectively cushion the shock when the pistons are ultimately forced or returned toward the connectors by the compression spring.

In my prior patent also the construction disclosed therein is such that the connectors are effectively tied to the wobble plate so that the wobble plate cannot rotate relatively thereto. Provision is also made for guiding the wobble plate during its wobbling action so as to hold it against rotation. I find that in a construction of

2

this character as the wobble plate is driven that it tends to rotate relative to the bearing on which it is supported and that the guide in holding the wobble plate against rotation due to the friction necessarily present causes some additional power to be unnecessarily supplied in driving the wobble plate.

An object of the present invention is to provide an approved pump or compressor wherein the wobble plate is not held against rotation and the connection between the pistons and the wobble plate is such that the wobble plate is free to rotate relatively thereto thus eliminating the unnecessary expenditure of power in overcoming the friction required to hold the wobble plate against rotation.

Still a further object of the invention is to provide a pump or compressor having the above described characteristics wherein the point of engagement between the connectors and the wobble plate is disposed well below the center about which the wobble plate wobbles so that as the wobble plate forces the connectors to move the pistons to the tops of their strokes the line of force throughout the length of strokes of the pistons will more closely approach the line of travel of the pistons.

With the foregoing and other objects in view, which will be made manifest in the following detailed description and specifically pointed out in the appended claims, reference is had to the accompanying drawings for an illustrative embodiment of the invention, wherein:

Figure 1 is a vertical section through the improved pump or compressor embodying the present improvements;

Fig. 2 is a sectional view taken substantially upon the line 2—2 upon Fig. 1 in the direction indicated; and

Fig. 3 is a sectional view through one of the pistons on a somewhat enlarged scale.

Referring to the accompanying drawings wherein similar reference characters designate similar parts throughout, the improved pump or compressor consists of a suitable housing or cylinder block 10 within which is rotatable a drive shaft 11 connected by an arm 12 to the column 13 of a wobble plate 14. Column 13 is preferably made up of telescopically arranged sections so as to be extensible or collapsible. It may be constructed similar to the disclosure made in Fig. 10 of my prior patent omitting screw 73 so as to enable telescopic movement to take place. The arm 12 may be in the nature of a leaf spring so as to be relatively stiff in an edgewise direction

but bendable or yieldable in a direction axially of the drive shaft 11. The wobble plate is mounted on a spherical bearing 15 so that as the drive shaft 11 is driven the wobble plate will wobble relatively to the bearing. Within the housing or cylinder block there are cylinders 16 arranged around the axis of rotation of the drive shaft 11 and the center of wobbling of the wobble plate. Within these cylinders there are pistons 17 which are urged toward the wobble plate by means of compression springs 18 disposed about the cylinder liners 19 and bearing on flanges 20 of the pistons. The pistons may be of integral construction or may be fabricated and likewise the wobble plate may be of a single integral construction or may be fabricated.

One feature of the invention concerns primarily the connection between the wobble plate and the pistons. The pistons have axial bores 22 extending therethrough. At the upper or head end of the piston there are valve seats 23 and spaced from these valve seats there are additional valve seats 24. The valve seat 24 is adequately large to permit of the insertion therethrough of a ball 25 adapted to seat on the valve seat 23 and urged to seat thereon by a compression spring 26 which can also be passed through the valve seat 24. Balls 27 are disposed in the passages or bores 22 and are adapted to seat on the seats 24. The connectors are illustrated at 28 having stems which telescope within the lower or skirt ends of the pistons and which are engageable with the balls 27. These connectors have heads 29 which engage the wobble plate 14. The heads have bevelled edges which are preferably slightly rounded as indicated at 30 which bear against or engage directly with the flat surface 31 of the wobble plate.

In the head of the housing or cylinder block 10 there may be a valve action which controls or regulates egress of gas or liquid from the cylinders 16. This valve action may conform to the valve action disclosed in my prior patent or it may be of any conventional design. I have illustrated ingress to the cylinders as being provided through ports 32 from passages 33. The ball 15 is equipped with a shank 34 having a washer or piston 35 secured thereto which is movable in a cylinder 36. Pressure may be supplied to this cylinder, such as by a conduit 37 that may be connected to the high side or outlet from the compressor or pump. The pressure so applied urges the ball 15 toward the drive shaft 11 and in this way a variation in the capacity of the compressor or pump is possible. Thus, if a low pressure is conducted to the cylinder 36, such as may be occasioned by a relatively light load the bearing 15 and the wobble plate supported thereon may recede from the drive shaft 11, thus allowing the pistons to recede from the cylinder head. Conversely, if a high pressure is conducted to the cylinder 36 the pistons may be advanced by the wobble plate toward the cylinder head so that the pressure at which the liquid or gas is delivered from the compressor or pump can be increased. Movement of the wobble plate toward and away from the cylinder head is permitted by the telescopic action of the column 13.

The operation and advantages of the above-described construction are as follows: Assuming that the drive shaft 11 is driven at relatively high speed so as to likewise cause the wobble plate 14 to likewise wobble at relatively high speed when the pistons are driven to the upper or head end of their strokes the inertia of the pistons is such that the springs 18 are incapable of causing the

pistons to be continuously urged toward the wobble plate. In other words, there may be instances when the wobble plate has its flat surface 31 receding from a given piston faster than the springs 18 can overcome the inertia of the piston and keep it pressed toward the wobble plate. As the construction disclosed herein is used as a compressor for gas a portion of the gas will enter the bores 22, pass the check valve 25 and be entrapped 10 therein by the check valve. This entrapped portion of the gas will have a pressure equal to the pressure to which the gas is compressed by the piston at the top or head end of the stroke. If the wobble plate 14 has its surface 31 receding 15 slightly from the piston because of the high speed at which it is driven and the inability of the springs 18 to instantly overcome the inertia of the piston, this entrapped gas under pressure will escape past valve 27 and become effective on the tops of the stems 28 to urge the connectors which are of relatively small masses to continue in engagement with the surface 31. Thereafter, spring 18 will overcome the inertia of its piston and cause the piston to take up the slack momentarily existing 20 between the piston and its connector. As this slack is taken up the top or end of the stem 28 acts as a piston tending to return the gas into the space between valve seat 24 and valve seat 23 thus recompressing the gas in this chamber to 25 approximately the pressure to which the gas is compressed by the piston when at the top or head end of its stroke. This recompression of the gas occasioned by the slack being taken up between the pistons and their connectors functions to 30 cushion the return of the pistons and their connectors to their normal positions thus eliminating objectionable noise, vibration, and pounding.

If the device herein illustrated is used as a 35 pump for pumping liquids which are relatively incompressible and inexpandable a liquid in the space between the valve seats 23 and 24 may trickle through valve seat 24 whenever the connector recedes from the ball 27 and such liquid will also effectively cushion the return of the pistons to its connector in that the liquid must be crowded back through the relatively small valve seat 24. Thus, even though a liquid is employed which is relatively incompressible and incompressible it will serve to cushion the returning movement between the piston and its connector. When a liquid is employed it is possible to dispense with the ball or valve 25 entirely and also spring 26.

It will be noted that in the above-described 40 construction there is no guide or any restraining means holding the wobble plate 14 against rotation relative to the spherical bar 15. I find that in this construction of this character that with continued operation the wobble plate will naturally tend to rotate relatively to the bearing and that if such movement is restrained additional power must be supplied to overcome the friction between the wobble plate and its restraining means. With the improved construction the wobble plate can freely turn relatively to its bearing and slide or otherwise move with relation to the heads 29 on the connectors. Thus, by avoiding friction between the wobble plate and any restraining means it is unnecessary to supply power to overcome the friction occasioned by the restraint.

It is to be further noted that the surface 31 is 45 disposed below or toward the left as viewed in Fig. 1 of the center of ball 15 which is the center of oscillation of the wobble plate. Such an arrangement is highly preferable in that as the

wobble plate wobbles a point on surface 31 passes through an arc the direction of which more closely approaches the line of travel of the connector and its piston. If the surface 31 were disposed in a plane coincident with the center of ball 15 such a point during its travel would tend to drop away from the axis of its cylinder much more rapidly than with the arrangement shown. Consequently, by having the surface 31 disposed below or to the left of the center of ball 15 the point of engagement between the surface and any connector more closely approaches the line of travel of the connector and of its piston during the movement of such point.

From the above-described construction it will be appreciated that the improved pump or compressor is so designed that it may be driven at quite high speeds without objectionable vibration wear or noise. Furthermore, as wear between the surface 31 and the heads 29 is distributed throughout the annular surface 30 the life of these parts is materially prolonged even under the most severe conditions.

Various changes may be made in the details of construction without departing from the spirit and scope of the invention as defined by the appended claims.

I claim:

1. A compressor or pump comprising means providing a wobble plate, means for driving the wobble plate, a plurality of cylinders arranged about the wobble plate, pistons reciprocable in the cylinders, spring means urging the pistons toward the wobble plate and connectors between the pistons and the wobble plate slideable toward the wobble plate relatively to their respective pistons and spring means urging said connectors toward said wobble plate relatively to their respective pistons.

2. A compressor or pump comprising means providing a wobble plate, means for driving the wobble plate, a plurality of cylinders arranged about the wobble plate, pistons reciprocable in the cylinders, spring means urging the pistons toward the wobble plate and connectors between the pistons and the wobble plate movable relative to their pistons toward the wobble plate and means for cushioning movements of the connectors toward the pistons.

3. A compressor or pump comprising means providing a wobble plate, means for driving the wobble plate, a plurality of cylinders arranged about the wobble plate, pistons reciprocable in the cylinders, spring means urging the pistons toward the wobble plate, connectors telescopically arranged in the pistons and engaging the wobble plate for reciprocating the pistons by the wobble plate and means for conducting fluid pressures in the cylinders to the connectors.

4. A compressor or pump comprising means providing a wobble plate, means for driving the wobble plate, a plurality of cylinders arranged about the wobble plate, pistons reciprocable in

the cylinders, spring means urging the pistons toward the wobble plate, connectors telescopically arranged in the pistons and engaging the wobble plate for reciprocating the pistons by the wobble plate and means for conducting fluid pressures in the cylinders to the connectors and entrapping it in the pistons against the connectors.

5. A compressor or pump comprising means providing a wobble plate, means for driving the wobble plate, a plurality of cylinders arranged about the wobble plate, pistons reciprocable in the cylinders, spring means urging the pistons toward the wobble plate, said pistons having passages therethrough, connectors reciprocable in

15 said passages and engaging the wobble plate so as to be operable thereby, there being a valve seat in each passage, and means for opening and closing said seat operable by the connectors reciprocating in their passages relative to the pistons.

6. A compressor or pump comprising means providing a wobble plate, means for driving the wobble plate, a plurality of cylinders arranged about the wobble plate, pistons reciprocable in the cylinders, spring means urging the pistons toward the wobble plate, said pistons having passages therethrough, connectors reciprocable in

25 said passages and engaging the wobble plate so as to be operable thereby there being spaced valve seats in the passages, balls adapted to seat thereon, a spring between the balls, the connectors being operable to open and close one of the balls toward its seat upon movement of the connectors relative to their respective pistons.

7. In a compressor or pump, a wobble plate, a bearing therefor about the center of which the wobble plate wobbles, means for driving the wobble plate, pistons reciprocable in cylinders arranged about the wobble plate and means on the pistons bearing against the wobble plate serving to advance the pistons thereby, the points of engagement between each of said means on their pistons and the wobble plate being disposed in a plane on the opposite side of the center of wobbling of the wobble plate, from the pistons.
